UNITED STATES PATENT OFFICE.

GERHARD DÜNNINGHAUS, OF UNNA, WESTPHALIA, ASSIGNOR, BY MESNE ASSIGNMENTS, TO ROBERT HINRICHSEN, OF HAMBURG, GERMANY.

BUSK FOR CORSETS.

SPECIFICATION forming part of Letters Patent No. 381,061, dated April 10, 1888.

Application filed September 8, 1885. Serial No. 176,471. (No model.) Patented in Belgium February 2, 1885, No. 67,728; in France February 10, 1885, No. 166,953; in England May 5, 1885, No. 5,535, and in Austria-Hungary July 19, 1885, No. 13,294 and No. 37,317.

To all whom it may concern:

Be it known that I, GERHARD DÜNNINGHAUS, of Unna, Westphalia, Germany, have invented certain new and useful Improvements in 5 Busks for Corsets, (for which patents have been granted in Belgium, No. 67,728, dated February 2, 1885; in France, No. 166,953, dated February 10, 1885; in England May 5, 1885, No. 5,535, and in Austria-Hungary, No. 13,294 10 and No. 37,317, July 19, 1885,) of which the following is a specification.

My invention relates to that class of corset busks or stays which are composed of an upper and a lower part or blade united by one 15 or more springs for the purpose of increasing their elasticity at the spot where breakages usually occur—namely, at the waist.

It consists in forming a joint by connecting two parts or blades of each busk by one or 20 more helical springs attached at their upper ends to the lower end of the upper part, and at their lower ends to the upper end of the lower part.

It also consists in certain features of detail, 25 as hereinafter described, and specified in the claims.

In the further description reference will be made to the accompanying drawings, of which—

30 Figure 1 is a front elevation of a pair of busks embodying my invention, while Fig. 2 represents a detail.

Each of the two busks or stays of a corset is made similar to those usually employed, except that it is divided at or near the middle of its length, so as to form two upper parts, A and B, and two lower parts, A' B', which are united by helical springs b b. I prefer to place the springs vertically or parallel to the 35 length of the busk and to employ two springs for each busk, as shown by the drawings. The wire from which the springs are made

may be round or flat, and the helix formed by each spring may be cylindrical, conical, or conoidal, and circular or flattened in cross- 45 section.

In order to obtain a simple and solid connection, I cut a diametrical slit, s, into each end t of the springs, then introduce the ends of the parts A and A', B and B', into the said 50 slits and secure them therein by solder.

Fig. 2 shows a spring b separately with the slit s at each end t.

What I claim is—

1. In a corset-busk, two superposed parts 55 or blades united by an elastic bending joint comprising one or more helical springs, each spring attached at one end to the upper part or blade and at its other end to the lower part or blade, substantially as set forth. 60

2. The combination, with the upper part of a corset-busk and with the lower part of said busk, of one or more helical springs interposed between the said upper and lower parts of the busk, the upper ends of the helical springs 65 being permanently attached to the lower end of the upper part of said busk, and the lower ends of said helical springs being permanently attached to the upper end of the lower part of the busk. 70

3. The combination, with the upper part of a corset-busk and with the lower part of said busk, of one or more helical springs slotted at their ends and secured to the upper and lower parts of the busk, substantially in the 75 manner described.

In testimony whereof I have signed my name to this specification in the presence of two subscribing witnesses.

GERHARD DÜNNINGHAUS.
